UNITED STATES PATENT OFFICE.

WILLIAM R. MILLER, OF PITTSBURG, PENNSYLVANIA, ASSIGNOR TO FORMER MILLER ENGINEERING CO., OF PITTSBURG, PENNSYLVANIA, A CORPORATION OF PENNSYLVANIA.

WATER-SEALED CONTINUOUS INGOT-HEATING FURNACE.

No. 849,909.

Specification of Letters Patent.

Patented April 9, 1907.

Application filed November 12, 1906. Serial No. 343,083.

To all whom it may concern:

Be it known that I, WILLIAM R. MILLER, a citizen of the United States, residing at Pittsburgh, in the county of Allegheny and State 5 of Pennsylvania, have invented certain new and useful Improvements in Water-Sealed Continuous Ingot - Heating Furnaces, of which the following is a specification, reference being had therein to the accompanying 10 drawings.

My invention relates to improvements in continuous heating-furnaces for ingots, billets, &c., and comprises a longitudinal furnace open at each end and provided with a 15 way through which ingot-buggies pass, having supporting-tracks laid along the foundation, the bottom portion of the furnace comprising a water-seal portion with submerged tracks, together with coating turn-tables arranged 20 for vertical movement and rotation to charge into and receive the ingot-buggies from the furnace.

The invention is an improvement on that class of furnace shown and described in Letters Patent No. 822,380, dated June 5, 1906, of Paul V. Cole and the present applicant.

In the drawings, Figure 1 is a vertical longitudinal sectional view, partly broken away, of my improved continuous ingot-heating 30 furnace. Fig. 2 is a horizontal sectional view on the line II II of Fig. 1. Fig. 3 is a partial similar view showing one end of the furnace and illustrating the manner in which the turn-table is turned to align with the furnace-tracks. Fig. 4 is a cross-sectional view, 35 on an enlarged scale, on the line IV IV of Fig. 1. Fig. 5 is a similar sectional view on the line V V of Fig. 1.

Referring now to the drawings, 2 represents the furnace-chamber, contained within 40 the longitudinal parallel side walls 3 3 and having a suitable roof 4 of any desired construction, as shown in the patent above referred to, whereby to provide preliminary heating of the air.

The construction as to the air and gas supply does not *per se* form an important part of the invention, and it is sufficient to state that the gas and air are introduced into the combustion-chamber 5, from whence the fuel in 50 combustion circulates throughout the interior of the furnace toward the opposite end, the products of combustion passing out-

wardly at one or both sides through outlet-pipe 6, connected with the stack in any suitable manner. At each end the furnace is provided with swinging or otherwise suitably mounted doors 7 8, adapted to fit down over or across the ends of the ingot-buggies and to close the ends of the furnace against entrance 60 of air or escape of the gases. The entire furnace construction is preferably provided with a supporting-framework of structural elements 9, as shown, or may be braced with the ordinary buckstaves, as desired. 65

The lower portion of the furnace-chamber throughout its full length constitutes a water-seal basin 10, the furnace being provided with tracks 11 along its bottom, terminating at each end, as shown. At each end of the 70 furnace structure is also provided a supplemental well or basin 12 12 immediately beyond the end walls, in which is mounted upon a piston-rod or hydraulic ram 13 a turn-table 14, provided with tracks 15 of the 75 same gage as tracks 11. The piston-rod or ram 13 projects upwardly into the basin 12 through a suitable stuffing-box 16 and is actuated by a piston or plunger secured upon its lower end and mounted in hydraulic, 80 steam, or other fluid-actuated cylinder 17. Said cylinders, as shown, are located at each end of the furnace structure within a suitable chamber and are provided with proper connections by which the flow of the fluid 85 may be easily controlled by the operator, as will be readily understood. Each piston-rod 13 is provided with a pinion 18 of sufficient length to maintain engagement with an actuating rack-bar 19 at varying vertical positions, by which construction the rod and its 90 superimposed turn-table may be rotated a quarter-revolution.

Other mechanism for the raising and lowering of the turn-table and also for accomplishing its rotation may be substituted for the above-specified construction. 95

The construction and arrangement of the supplemental basins 12 is such as to permit of the lowering of the turn-tables 14 downwardly until tracks 15 will align with tracks 11 and on the same level therewith below the ordinary level or may be raised above the water-level to align with tracks 20. By such construction the ingot-buggies may be run 100 onto and off from the turn-tables above the 105

water-level, and it will be seen that each buggy is thus independently manipulated vertically and rotatably with relation to the upper and lower tracks.

5 The buggies may be of any suitable construction or design and may be provided with means for coupling them together in the usual way, and when run into the furnace it will be noted that practically the entire lower 10 portion of the buggy structure will be submerged below the water-level, so that the upper portion carrying the ingots or other articles to be treated is exposed. By reason of the continuation of the water seal through- 15 out the full length of the furnace and also of the basins 12 12 a continuous water seal is provided, through which the buggies pass in their progress into, through, and out from the furnace. By this means the circulation 20 of the gases into contact with the ingots, &c., is in no way impeded, while escape of any gas is entirely prevented.

The operation will be readily understood from the foregoing description. The invention 25 as a whole is simple, efficient, and capable of long-continued operation without liability to get out of order.

The features of improvement may be applied to various constructions of furnaces or 30 incorporated with existing constructions and may also be changed or varied by the skilled mechanic as to different details; but all such changes or variations are to be considered as within the scope of the following claims.

35 What I claim is—

1. In a furnace having a bottom and tracks thereon, and means for submerging and keeping submerged such bottom and tracks, the combination with tracks leading 40 to the furnace at a higher level, of a vertically-adjustable turn-table adapted to align with each of said tracks respectively, substantially as set forth.

2. A continuous furnace provided with a 45 bottom and a pit, means for submerging and keeping submerged such bottom, and vertically-adjustable supporting mechanism arranged to locate a traveling buggy or the like with relation to the bed of the furnace, substantially as set forth.

3. A continuous furnace provided with 50 tracks and a pit at each end, means for submerging the tracks and keeping them submerged, and vertically-adjustable devices 55 mounted in said pits arranged to locate a traveling buggy or the like with relation to the bed of the furnace, substantially as set forth.

4. A continuous furnace provided along 60 its bottom with supporting-tracks, means for submerging said bottom and tracks, a lower chamber at each end of the furnace

communicating therewith, upper tracks leading thereto, and a vertically-adjustable turn-table having tracks arranged to be lowered 65 into registering alinement with the furnace-tracks and to be raised into alinement with the upper tracks, substantially as set forth.

5. The combination with a continuous furnace provided with tracks along its bottom, 70 a communicating chamber, means for submerging the furnace bottom, tracks and chamber, and a vertically-adjustable buggy-supporting device having tracks, adapted to be lowered into alinement with the tracks of 75 the furnace, substantially as set forth.

6. The combination with a continuous furnace provided along its bottom with tracks, communicating chambers at each end, means for submerging the furnace bottom, tracks 80 and chambers and for keeping them submerged, vertically-adjustable turn-tables having tracks located in said chambers, supplemental tracks leading to said turn-tables at a higher level, and means for raising and 85 lowering the turn-tables, substantially as set forth.

7. The combination with a continuous furnace provided along its bottom with tracks, communicating chambers at each end, means 90 for submerging the furnace bottom, tracks and said chambers, vertically-adjustable turn-tables having tracks located in said chambers, supplemental tracks leading to said turn-tables at a higher level, and means 95 for raising, lowering and turning the turn-tables, substantially as set forth.

8. The combination with a continuous furnace provided with tracks and a communicating chamber, upper tracks leading to said chamber, and means for submerging said tracks and chamber, of a vertically-movable stem supporting a turn-table in said chamber having tracks arranged to align with said furnace-tracks and with the upper tracks, 100 rack-and-pinion mechanism for rotating the stem and turn-table, and fluid-actuated mechanism for raising and lowering the turn-table, substantially as set forth.

9. The combination with a furnace having 110 a supporting-bottom and means for submerging said bottom, of a track leading to a higher level, a lower chamber communicating with the furnace interior, and a vertically-adjustable support mounted in said 115 lower chamber arranged to be located in alinement with the furnace-bottom and with said higher track, substantially as set forth.

In testimony whereof I affix my signature in presence of two witnesses.

WILLIAM R. MILLER.
